(57) **CLAIM**

I claim the ornamental design for a stake connector, as shown and described.

DESCRIPTION

FIG. 1 is a front view of a stake connector, with the stake illustrated with broken lines;

FIG. 2 is a perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines in the drawings are for showing portions of the article and form no part of the claimed design.
